UNITED STATES PATENT OFFICE

THEOPHILUS BROWN, OF MOLINE, ILLINOIS, ASSIGNOR TO DEERE & COMPANY, OF MOLINE, ILLINOIS, A CORPORATION OF ILLINOIS

GANG PLOW

Application filed July 21, 1921. Serial No. 486,642.

My invention relates to gang plows, particularly to that type in which a series of plowing disks is mounted on a diagonally disposed wheel supported beam, and the object of 5 my invention is the production of certain novel and efficient features of construction, operation and adjustment, which will be clearly outlined in the following specification.

10 Referring to the drawings in which similar numerals indicate identical parts—

Figure 1 is a plan view of a wheel supported disk plow embodying my invention. Figure 2 is a side elevation illustrating the 15 position of the parts when the plow is in operation. Figure 3 is a rear elevation in part of Figure 1. Figure 4 is a view similar to Figure 3 but showing the plow raised. Figure 5 is a detail side elevation of the position 20 of the power lift parts and connections when the plow is raised and viewed in the direction of the arrow in Figure 4. Figure 6 is a detail view in part section on the line 6—6 of Figure 1 and looking forward. Figure 7 is a detail 25 illustrating the attachment to the plow beam of the standards supporting the disks, and Figure 8 is a detail part section of parts on the upper ends of the furrow wheel crank axles.

30 The frame of the plow includes a rear casting 2, extending transversely at a right angle to the line of draft, a draw bar 3, parallel to the casting 2 and rigidly secured to a casting 4, and a beam 1 extending diagonally in a furrowward direction from the casting 2 to connection with the casting 4. The beam 1 is preferably square in cross section and is mounted in such a manner that the diagonals 35 of the square are respectively vertical and horizontal, this disposition of the beam presenting the greatest resistance to vertical and horizontal strains. The rear end of the beam 1 is secured in a block 5, preferably integral with the casting 2, by a cap 6 bolted to the block 5, and the forward end of the beam 1 is similarly secured on a rear extension 7 of the casting 4 by a cap 8 bolted thereon. A brace 9 is secured to the landward end of the drawbar 3, and extends rearwardly to rigid connection with the beam 1.

The plows 10 are mounted respectively on standards 11 and 12. Each standard is secured to the beam 1 by clamps one part 13 of which is preferably integral with the standard, and to which the second part 14 is secured by suitable bolts which can be readily loosened to permit adjustment of the standards and the plows along the beam to regulate the width of furrow it is desired to cut.

On the casting 4 is a bearing 15 in which is 55 slidably supported the vertical spindle 16 of a crank axle having a furrow wheel 17 journaled on its lower end. A split elbow 18 is rigidly secured on the bend of the axle and bolted to the elbow 18 is a forwardly extending bar 19 normally parallel with a draft bar, formed of parallel bars 20 and 21, having its rear end secured to a coupling 22 by a vertical pivot 23, and its forward end adapted to be attached to a tractor. The coupling 22 60 is pivotally connected to a clevis 24 bolted to the draw bar 3, the latter having a series of holes 25 for lateral adjustment of the clevis as occasion may require. A bar 26, 65 composed of superimposed bars 27 and 28 bolted together, is provided with a series of holes whereby the length of the bar 26 can be readily changed when desired. The bar 26 connects the bar 19 with the draft bar and any lateral deviation of the latter from parallelism with the direct line of draft steers the furrow wheel 17 correspondingly.

70 Preferably integral with the casting 4 and extending transversely of the plow is a bearing 29 and journaled therein is a rock shaft 31 having its furrowward end 30 bent to extend forwardly and pivotally connected to a vertically disposed rod 31 threaded at its upper end to engage with a threaded opening in an eye-bolt 32 and secured from longitudinal movement by a nut on the end of the rod. The eye-bolt 32 is pivotally secured in a cap 33 loosely mounted on the upper end of the spindle 16 in order that the latter may 75 turn freely therein; withdrawal of the spindle from the cap is prevented by a collar 34 which is rigidly secured to the spindle 16 by a set screw 35 which projects through a horizontal slot 36 in the cap 33.

80 A manually operable lever 37 is rigidly 100

connected to one arm of a bell crank 38 pivotally mounted on the shaft *a*. A notched sector 39 is loosely supported on the landward end of the shaft *a* and is fixedly secured to a bracket 40 rigidly mounted on the casting 4; the lever 37 is provided with the usual type of latch to engage with any one of the notches in the sector 39. Pivotally connected to the rearward arm of the bell crank 38 is a bar *c* which extends rearwardly to an arm 41 on the furrowward end of a crank axle 42 and preferably integral therewith. The crank axle 42 is rotatably journaled in suitable bearings on the casting 2 and extends transversely of the plow. On the landward or crank end of the axle 42 is mounted a landwheel 43 with respect to which the frame is raised or lowered by operating the lever 37 to rock the axle 42.

On a rearward extension *b* of the casting 2 is a bearing 44 in which is slidably and rotatably journaled a vertical spindle 45 forming part of a crank axle on the crank end of which is mounted the rear furrow wheel 46.

On the end of the extension *b* is pivotally supported a bell crank 47 reenforced by a brace 48 which is secured to the pivot of the bell crank and extends parallel with the latter to its rear termination, the brace is then bent upon itself toward the bell crank and is securely bolted thereto. To the forward arm of the bell crank 47 a vertical rod 49 is pivotally attached, the upper end of said rod is threaded to engage with the threaded eye of a bolt 50 which is loosely held in a transverse hole in a cap 51, mounted on the upper end of the spindle 45, and held therein by a pin or cotter. The cap 51 is held on the spindle 45 by a collar 52 rigidly secured on the spindle 45 by a set screw 53 which extends through a horizontal slot 54 in the cap 51.

Pivotally connected to the rear arm of the bell crank 47 is a link 55 which extends forwardly to connection with an upstanding arm 56 preferably integral with a rock shaft 57 parallel with the axle 42 and supported in bearings 58 and 59 on the casting 2. At the pivotal connection of the link 55 with the arm 56 is connected a bar 60 which extends forwardly to pivotal attachment to an arm 61 which is part of a manually operable lever 62 pivotally mounted, at the bend of the arm 61, on a standard 63 rigidly secured on the shaft *a*. To the pivot of the lever 62 is secured a radius arm *d* of a notched sector 64 which is further supported on a vertical link 65 pivotally connected to the arm *d* and to a bracket 66 on the casting 4. The lever 62 is provided with the usual type of latch to engage with the notches in the sector 64.

Extending forwardly from the casting 4 is an arm 67 with a forwardly upturned end carrying an eyebolt 68 to which is connected a coiled spring 69 the other end of which is connected to a loop 70 which passes around

the standard 63 and is secured to a projection on the rear side thereof.

The traction power of the landwheel 43 is utilized to raise the furrowward side of the plow only, by the operation of mechanism well known in the art and including a clutch comprising driving and driven clutch parts 82 and 83 respectively, (Fig. 1) both concentrically mounted in alinement with the landwheel, the driving part 82 being secured to the landwheel and the driven part 83 being connectible to the first part at will by actuation of a tripping lever 71 controlled by a cable 72 from the tractor by which the plow is to be drawn. The lifting link 73 in this instance extends from the second part of the clutch to connection with an arm 74 preferably integral with the landward end of the rock shaft 57 and projecting upwardly therefrom.

Figures 2 and 3 illustrate the position of the plow when in operation; when it is desired to raise the plow out of operative position rocking the tripping lever 71 will cause the parts of the clutch to engage and rotate with the wheel 43, and as the link 73 is actuated by the part of the clutch to which it is connected and is connected to the arm 74 of the transverse rock shaft 57, the latter is rocked forwardly and through the arm 56, preferably integral therewith, the bars 55 and 60 are also moved in a forward direction. The forward movement of the bars 55 and 60 rocks the bell crank 47 and simultaneously the shaft *a* through the standard 63, rigidly mounted thereon, and carrying the lever 62 to the bent end of which the bar 60 is pivotally connected, the lever 62, when locked to the sector 64, acting practically as a continuation of the bar 60, and as the sector 64 is pivotally supported on the standard 63 and the pivoted link 65 it moves forwardly with the movement of the bars 55 and 60 so that its relative position with the lever 62 is never disturbed. As heretofore explained the bell crank 47 is connected to a rod 49 attached to a cap 51 on the upper end of the spindle 45 of the rear furrowwheel axle, and the arm 30 of the rock shaft *a* is connected to a similar rod 31 attached to a cap 33 on the upper end of the spindle 16 of the front furrowwheel axle; consequently when the bell crank 47 and the shaft *a* are rocked the furrowward side of the plow is raised moving upward freely on the spindles 16 and 45, the operation being materially assisted by the coiled spring 69 and a similar spring 75 extended between a bracket 76 on the bell crank 47 and a bracket 77 on the arm 41 of the axle 42.

The depth at which it is desired the plow shall operate is controlled by the levers 37 and 62, the lever 62 operating to raise or lower the furrowward side of the plow on the front furrow wheel through the connections therewith described, and the lever 37 operating

to rock the axle 42 to adjust the plow for the depth desired. Steering the plow is effected by lateral swing of the draft bar, the front furrow wheel 17 freely following the lead of the draft bar through its connecting bars 19 and 26. The rear furrowwheel is held from swinging by a rod 78 secured to a bracket 79 on the casting 2 and to an arm 80 rigidly secured on a split sleeve 81 on the rear furrowwheel axle. It will be seen from the above description that the transverse member or casting 2 is adjustable fore and aft along the beam 1 to accommodate a greater or lesser number of furrow opener units, and that all the parts operatively mounted upon such transverse member, including the land wheel and the rear furrow wheel, will maintain their proper operating relationship and be bodily shifted along with it when it is so adjusted fore and aft. Referring to Fig. 1, it will be seen that each motion transmitting bar *c* and 60 is constructed of two parallel, relatively adjustable bar sections joined by bolts *c'* and 60' which permit the effective lengths of these bars to be extended or contracted for accommodating the fore-and-aft shifting of the transversely extending frame member 2.

By the construction and operation shown and described less power is required than in structures of a similar kind in which the entire body is raised.

What I claim is—

1. In a power lift gang plow, the combination of a frame including a plow-carrying beam, front and rear furrow wheels, a landwheel, means operable to adjust said frame relatively to the landwheel to vary the depth of plowing, and mechanism independent of said means and actuated by power from one of said wheels to raise the furrowward part of the frame relatively to said furrow wheels irrespective of adjustment of the landward part thereof with respect to the land wheel.

2. In a power lift gang plow, the combination of a frame including a plow-carrying beam, front and rear furrow wheels, a landwheel, a lever, connections operable thereby to vertically adjust the frame relatively to the landwheel, and mechanism actuated by power from the landwheel and operable independently of said lever to raise the furrowward part of the frame relatively to said furrow wheels irrespective of adjustment of the landward part thereof with respect to the land wheel.

3. In a power lift gang plow, the combination of a frame including a plow-carrying beam, front and rear furrow wheels, a landwheel, a lever, connections operable thereby to vertically adjust the frame relatively to the landwheel, a second lever, connections operable by the latter lever to vertically adjust the frame relatively to one of the furrow wheels, and mechanism actuated by power

from the landwheel and operable independently of said first-mentioned lever to raise the furrowward part of the frame irrespective of adjustment of the landward part thereof with respect to the land wheel.

4. In a power lift gang plow, the combination of a frame including front and rear members and a plow-carrying beam, front and rear furrow wheels, a transverse crank axle rockably journaled in bearings on the frame, a landwheel on said axle, manually operable means for rocking said axle, a rock-shaft supported in bearings on the frame, and mechanism independent of said manually operable means and actuated by traction power of one of the wheels to rock said rock-shaft to raise the furrowward part of the frame relatively to said furrow wheels irrespective of adjustment of the landward part thereof with respect to the land wheel.

5. In a power lift gang plow, the combination of a frame including front and rear members and a plow-carrying beam, front and rear furrow wheels, a transverse crank axle rockably journaled in bearings on the rear frame member, a landwheel on said axle, manually operable means for rocking said axle, a rock-shaft supported in bearings on the frame, and mechanism independent of said manually operable means and actuated by traction power of the landwheel to rock said shaft to raise the furrowward part of the frame relatively to said furrow wheels irrespective of adjustment of the landward part thereof with respect to the land wheel.

6. In a power lift gang plow, the combination of a frame including front and rear members and a plow-carrying beam, front and rear furrow wheels, a landwheel, manually operable means to raise or lower the landward part of the frame to regulate the depth of plowing, means independent of said manually operable means and actuated at will by traction power of the landwheel to raise the furrowward part of the frame relatively to said furrow wheels irrespective of adjustment of the landward part thereof with respect to the land wheel and manually operable means for raising or lowering the furrowward part of the frame.

7. In a power lift gang plow, the combination of a frame including front and rear members and a plow-carrying beam, front and rear furrow wheels, a transverse crank axle rockably journaled in bearings on the frame, a landwheel on said axle, a lever operable to rock said crank axle, a second lever operable to adjust the frame vertically relatively to one of the furrow wheels, a rock-shaft supported in bearings on the frame, and mechanism independent of said first-mentioned lever and actuated by traction power of the landwheel to rock said rock-shaft to raise the furrowward part of the frame relatively to said furrow wheels irrespective of adjustment of the landward part thereof with respect to the land wheel.

of the landward part thereof with respect to the land wheel.

8. In a power lift gang plow, the combination of a frame including a plow-carrying beam, front and rear furrow wheels, a landwheel, means operable to adjust said frame relatively to said landwheel, a clutch mounted concentrically with the landwheel, means for engaging said clutch, and means actuated by power derived from said clutch for raising the furrowward part of the frame relatively to said furrow wheels irrespective of adjustment of the landward part thereof with respect to the landwheel.

9. In a power lift plow, the combination of a frame including a plow-carrying beam, front and rear furrow wheels, a landwheel, a lever, connections operable thereby to vertically adjust the frame relatively to the landwheel, a clutch mounted concentrically with respect to said landwheel and having one element driven thereby, means for engaging said clutch, and means actuated by power derived from said clutch for raising the furrowward part of the frame relatively to said furrow wheels irrespective of adjustment of the landward part thereof with respect to the landwheel.

10. In a power lift gang plow, the combination of a frame including a plow carrying beam, front and rear furrow wheels, a landwheel, a lever, connections operable thereby to vertically adjust the frame relatively to said landwheel, a second lever, connections operable by said latter lever to vertically adjust the frame relatively to one of said furrow wheels, clutch mechanism comprising two cooperating alined clutch elements disposed concentrically with the axis of said landwheel, with one of said clutch elements driven thereby, means for engaging said clutch, and means actuated by power derived from the other clutch element and operable independently of said first mentioned lever to tilt said frame laterally around said landwheel as a fulcrum.

11. In a power lift gang plow, the combination of a frame including front and rear members and a plow carrying-beam, front and rear furrow wheels, a transverse crank axle rockably journaled in bearings on the frame, a landwheel on said axle, manually operable means for rocking said axle, a rock shaft supported in bearings on the frame, clutch mechanism comprising cooperating alined clutch elements disposed concentrically with said landwheel with one of said clutch elements driven thereby, means for engaging said clutch mechanism, and power transmitting mechanism actuated by the other of said clutch elements and operating through said rock shaft to raise the furrowward part of said frame independently of pivotal motion of said crank axle, whereby said frame

will be tilted laterally with said landwheel acting as a fulcrum on the ground.

12. In a power lift gang plow, the combination of a frame comprising a transversely extending portion adjacent the rear end thereof, a transverse crank axle rockably journaled in said transversely extending frame portion, a landwheel on the landward end of said crank axle, a rear furrow wheel supported at the furrowward side of said transversely extending frame portion with its axis slightly in rear of the axis of said landwheel, a front furrow wheel supported at the front end of said frame, a lever pivoted at the front portion of said frame, means operatively connecting said lever with said crank axle for rocking the latter, a second lever supported at the front portion of said frame and operatively connected to adjust said frame vertically relatively to said front furrow wheel, clutch mechanism comprising two cooperating clutch elements alined with the axis of said landwheel and swinging therewith, one of said clutch elements being driven by said landwheel, means for engaging said clutch elements, a rock shaft journaled in bearings in said transversely extending frame portion and being disposed substantially parallel to said crank axle, link means operatively connecting the driven clutch element with one end of said rock shaft, and means transmitting lifting power from the other end of said rock shaft to both of said furrow wheels and independently of said first mentioned lever, whereby engagement of said clutch is effective to tilt the furrowward part of said frame upwardly with said landwheel acting as a fulcrum on the ground.

13. In a power lift gang plow, the combination of a frame comprising a transversely extending portion adjacent the rear end thereof, a land wheel supported at the rearward end of said transversely extending frame portion, a furrow wheel supported at the furrowward end of said transversely extending frame portion with its axis disposed slightly in rear of the axis of said landwheel, a lever, means operable thereby for changing the relative position of said landwheel and said frame, a clutch mechanism comprising a clutch element driven by said landwheel, means for engaging said clutch mechanism, and means deriving power from the other element of said clutch mechanism and cooperating with said furrow wheel for tilting said frame laterally with said landwheel acting as a fulcrum on the ground.

14. In a gang plow the combination of a frame comprising a fore and aft adjustable transversely extending portion adjacent the rear end thereof, a land wheel supported at the landward end of said transversely extending frame portion, a furrow wheel connected with and supported by the furrow-

ward end of said transversely extending frame portion, an adjusting lever mounted on the front portion of said frame, and connecting means for transmitting motion from said lever to said furrow wheel for tilting said frame laterally with said landwheel acting as a fulcrum on the ground, said connecting means being adjustable to accommodate fore-and-aft shifting of said transversely extending frame portion.

15. In a gang plow, the combination of a frame comprising a fore and aft adjustable transversely extending portion adjacent the rear end thereof, a landwheel adjustably supported at the landward end of said transversely extending frame portion, a bell crank lever pivotally mounted adjacent the furrowward end of said transversely extending frame portion, a furrow wheel mounted upon 20 the transversely extending frame portion and operatively connected to said bell crank lever, and power lift means operated by the traction power of the land wheel for actuating said bell crank lever for causing the furrowward 25 side of said frame to tilt upwardly around a pivotal center defined by the point of contact of the landwheel with the ground, said land wheel, bell crank lever, furrow wheel and power lift means being shiftable as a unit 30 with said transversely extending frame portion in the fore-and-aft adjustment of the latter.

16. In a power lift gang plow, the combination of a plow beam extending diagonally 35 to the line of draft, a front furrow wheel adjustably supporting the front end of said plow beam, a transversely extending frame member mounted on the rear portion of said plow beam, a rear furrow wheel supported at the 40 furrowward end of said transversely extending frame member, a land wheel at the landward end of said frame member, a crank axle for said land wheel carried by said frame member, a power lift clutch driven by said 45 land wheel, a rock shaft carried by said frame member and operatively connected to said clutch, and means for transmitting power lift energy to said furrow wheels, said transversely extending frame member being shiftable fore-and-aft along said plow beam, and 50 said rear furrow wheel, land wheel, crank axle, power lift clutch and rock shaft being movable therewith as a unit in such fore-and-aft shifting.

55 THEOPHILUS BROWN.
